UNITED STATES PATENT OFFICE.

PERRY O. POWELL, OF MILWAUKEE, WISCONSIN.

DESIGN FOR A PIN OR ARTICLE OF SIMILAR NATURE.

Application filed July 14, 1926. Serial No. 18,360. Term of patent 14 years.

To all whom it may concern:

Be it known that I, PERRY O. POWELL, a citizen of the United States, residing at Milwaukee, in the county of Milwaukee and State of Wisconsin, have invented a new, original, and ornamental Design for Pin or Article of Similar Nature, of which the following is a specification, reference being had to the accompanying drawing, forming part thereof.

In the drawing, Fig. 1 is a front view of the pin or article of similar nature, showing my new design; and Fig. 2 is an edge view thereof.

I claim:

The ornamental design for a pin or article of similar nature, as shown.

PERRY O. POWELL.
